UNITED STATES PATENT OFFICE

96,599

DESIGN FOR A BRUSH

Jack Gilbert and Henry Parry, Erie, Pa.

Application June 25, 1935, Serial No. 57,399

Term of patent 14 years

To all whom it may concern:

Be it known that we, Jack Gilbert and Henry Parry, citizens of the United States, residing at Erie, in the county of Erie and State of Pennsylvania, have invented a new, original, and ornamental Design for a Brush, of which the following is a specification, reference being had to the accompanying drawing, forming part thereof.

We claim:

The ornamental design for a brush, as shown.

JACK GILBERT.
HENRY PARRY.
